Primary Examiner — Jack Reickel*Assistant Examiner* — Bobby W Jones, II(74) *Attorney, Agent, or Firm* — WENDEROTH, LIND & PONACK, L.L.P.(57) **CLAIM**

The ornamental design for a handspray, as shown and described.

DESCRIPTION

FIG. 1 is a perspective view of a handspray showing our new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines illustrate portions of the handspray that form no part of the claimed design.
